UNITED STATES PATENT OFFICE.

FRANCIS HODGKINSON, OF EDGEWOOD PARK, PENNSYLVANIA, ASSIGNOR TO THE
WESTINGHOUSE MACHINE COMPANY, A CORPORATION OF PENNSYLVANIA.

MULTISTAGE TURBINE.

957,338.

Specification of Letters Patent. Patented May 10, 1910.

Application filed February 26, 1907. Serial No. 359,468.

To all whom it may concern:

Be it known that I, FRANCIS HODGKINSON, a subject of the King of Great Britain and Ireland, and a resident of Edgewood Park, 5 in the county of Allegheny and State of Pennsylvania, United States of America, have made a new and useful Invention in Multistage Turbines, of which the following is a specification.

10 This invention relates to multi-stage elastic fluid turbines.

In the design and construction of elastic fluid turbines to run at relatively slow speeds, there are a number of things to be 15 taken into consideration, among which are, first, cost, which, of course, depends largely upon design and weight, the cost being closely related to the amount or weight of material used in this class of apparatus, and, 20 second, efficient steam utilization, which, to a large extent, is dependent upon the kind of stage divisions and the manner of utilizing the working fluid thermal energy therein—that is, the manner in which the thermal 25 energy of the working fluid is transformed into kinetic energy in the form of fluid velocity and the way in which the fluid velocity is absorbed.

It has been found that by combining in 30 an organized turbine two or more stages in which relatively great pressure drops occur, utilizing what may be termed high pressure working fluid, and a number of stages in which relatively small pressure drops occur 35 for utilizing what may be termed low pressure working fluid, an efficient turbine of relatively slow speed can be obtained, which, on account of its compactness is comparatively cheap to build.

40 The stages in which the relatively great pressure drops occur, and which are the high pressure stages, that is, those utilizing working fluid from initial terminal pressure down to a relatively low terminal pressure, and the 45 stages in which the relatively small pressure drops occur and which are the low pressure stages, that is, those utilizing the working fluid from the terminal exhaust pressure of the last high pressure stage down to the 50 main exhaust terminal pressure of the organized turbine, which may either be atmospheric or condenser pressure, are arranged to operate in series within a shell or casing which houses the complete organized turbine. The object had in view, therefore, has

been to produce an organized relatively slow speed turbine which is not only efficient in its utilization of the working fluid, but which is compact and, therefore, relatively light and cheap to manufacture. 60

In the drawings accompanying this application: Figure 1 is a longitudinal section of a turbine embodying this invention; and, Fig. 2 is a view illustrating the nozzle and blading lay-out utilized in the turbine represented in Fig. 1. 65

The turbine rotor comprises running wheels 3, 4 and 5, two blade carrying drums 6 and 7 and a balancing disk or piston 8, all mounted upon a common shaft 9. The shaft 70 9 is journaled within suitable bearings 10 adjacent its opposite ends and projects through the ends of the housing for the organized apparatus.

The housing, the upper portion of which 75 is numbered 11, while the lower portion is numbered 12, is divided in a horizontal plane passing through the axis of shaft 9. The housing is interiorly divided into compartments which accommodate the several 80 elements comprising the rotor; that is, diaphragm partition 13 forms a compartment or chamber for the balancing disk 8; while diaphragm partitions 14, 15 and 16 form compartments for the running wheels 3, 85 4 and 5.

The several partitions extend from the casing inwardly to within close proximity of the turbine shaft, or, more properly, the hubs for the several elements comprising 90 the rotor, and between said hubs and the partitions, removable sleeves or bushings 17 are placed. Between the inner surfaces of each of these bushings and the adjacent surfaces of said hubs, a labyrinth packing device is utilized, whereby each compartment 95 is effectively sealed from the one adjacent thereto.

The sleeves or bushings between the compartment for running wheel 3 and the compartment for the balancing disk is formed 100 in two parts with an intervening space 18 therebetween. This space leads into a chamber 19 lying between partitions 13 and 14 and which communicates with the compartment for running wheel 4 by means of a passage 20 in order that the working fluid leaking from the chamber for the balancing disk may be led to a part of the turbine 105 where it may perform useful work. 110

5 A passage 21, shown by dotted lines, is cored in the outer casing and connects the chamber for the balancing disk 8 and that part of the interior of said housing where the working fluid pressure equals the pressure at the inlet side of the first row of blades carried on drum 6. This is rendered necessary because the exhaust pressure on the inlet side of drum 6 equals the terminal exhaust pressure of the last high pressure stage, while the exhaust side of drum 7 is subject to the main exhaust pressure of the turbine, which may either be atmospheric or condenser pressure.

10 15 In order that balancing disk 8 may be effective as a balancing means for both drums 6 and 7, a labyrinth packing device 22 is interposed between the periphery of this disk and the adjacent surface of the 20 housing, and a passage 23 connects the side of the balancing disk opposite passage 21 with the main exhaust 24 of the turbine.

15 25 In the high pressure stages utilizing running wheels 3, 4 and 5, owing to the relatively great drops in pressure, it becomes necessary to fractionally abstract the fluid velocity and, therefore, each running wheel 3, 4 and 5 is provided with a plurality of annular rows of blades 25 and suitable intermediate guide vanes 26. In the stages employing wheels 3, 4 and 5 and where the 30 volume of working fluid is small, only a part of each wheel is active and nozzles 27, 28 and 29 are arranged in series or groups, 35 which groups only embrace a limited arc of the circumference of each wheel. The arc embraced by the nozzles 28 will be greater than that embraced by nozzles 27, owing to the increased volume of the working fluid; 40 so, also is the arc embraced by nozzles 29 greater than that embraced by nozzles 28. If desired these nozzles may be grouped and the groups separated and disposed at intervals around the wheel circumference.

45 50 Nozzles 27, 28 and 29 are so formed and proportioned as to convert the desired amount of thermal energy of the working fluid passing therethrough into kinetic energy in the form of fluid velocity and they are so positioned as to efficiently discharge the working fluid against the first row of 55 each series of blades 25 carried by the respective wheels. The intermediate guide vanes, of course, are utilized to re-direct the fluid issuing from the first set of blades 25 and direct it into the last row of blades 25 of each series, whereby the fluid velocity, due to the transformation in the nozzles, is fractionally abstracted. Drums 6 and 7 60 carry a plurality of annular rows of blades 30, (eight such rows being shown in the drawings) while the casing surrounding these drums carries a plurality of annular rows of stationary fluid directing vanes or 65 nozzles 31. These blades 30 and vanes 31

may be of any desired shape or formation and the number of rows may be increased or diminished as found desirable. In the drawings, however, I have shown what may be termed "Parsons" blading and the working fluid in its passage through the blades and vanes 30 and 31 will be fractionally expanded, whereby energy will be derived both by impulse and by reaction. This type of blading, however, is not necessary and this 70 invention contemplates the use of purely impulse blades for the blades 30 or impulse and reaction blades as shown.

75 Since vanes 31 are arranged in full annular rows, each stage from the exhaust of the high pressure stage, employing wheel 5, to the main exhaust of the turbine is of the full peripheral admission or total injection type, while each of the high pressure stages is of the partial flow injection type. By 80 using full annular rows of vanes 31, all of the blades 30 may be mounted on a single drum, or on two drums, which, as shown in the drawings, in effect, constitute a single drum. This arrangement renders unnecessary the partitions used between the high pressure stages and at the same time decreases the actual length of the turbine.

85 90 As shown in the drawings, the nozzles 27, 28 and 29 are supported in the partitions between the running wheel compartments. As the diameters of the running wheels and the drums 6 and 7 are substantially the same, and as the fluid velocity in each of the running wheels is abstracted in two operations, 95 while in the stages employing drums 6 and 7 the fluid velocity of each stage is abstracted in a single operation, it follows that the velocity of the working fluid is greater in the high pressure stages than in the low 100 pressure stages. Of course, it will be understood that if desirable a greater pressure drop may be utilized in the stage employing wheel 3 than in the stage employing wheel 4. Also a greater pressure drop may be 105 employed in the stage employing wheel 4 than that employed in wheel 5, and when such is the case, the number of annular rows of blades carried by the respective wheels will be varied to accommodate the pressure drop; that is when a greater pressure drop occurs in the stage employing wheel 3 than in the stage employing wheel 4, three rows of moving blades may be rendered necessary. 110 Of course, this will necessitate two rows of 115 intermediate guide blades. The proportioning of the pressure drops in the high pressure stages may be varied from what is shown in the drawings and still fall within the spirit of this invention.

120 125 If desirable the number of wheels employed in the high pressure stages may be diminished; that is, the turbine may be constructed so as to have but one or two running wheels and as the pressure drop will 120

then be greater for each stage employing the wheels, the number of rows of wheel buckets will be increased correspondingly.

The working fluid which is admitted to 5 nozzles 27 passes into the turbine through inlet port 32 and may be controlled in any manner desired. The governing of the turbine may either be accomplished by cutting in and out certain nozzles or groups of nozzles 27 and for overloads running wheel 3 10 may be by-passed to admit pressure working fluid to nozzles 28.

It will be understood that the pressures on 15 opposite sides of each running wheel are substantially the same; therefore, there is practically no axial thrust exerted on the shaft by said running wheels to counterbalance. The axial or endwise thrust of the composite drum 6-7, subject to different 20 pressures on its opposite faces, it is understood, is balanced by means of balancing piston or disk 8, which, on its opposite faces, is subjected to the same pressures as the composite drum 6-7 by means of passages 25 21 and 23.

I have shown and described one means for 30 obtaining a higher velocity in the high pressure stages than in the low pressure stages, but it is to be understood that the invention 35 in its broader aspects is not specifically limited thereto, since the desired relation of steam velocities in the different stages can be obtained by other means, as is well understood in the art to which this invention relates.

In accordance with the provisions of the 40 patent statutes I have described the principle of operation of my invention, together with the apparatus which I now consider to represent the best embodiment thereof, but I desire to have it understood that the apparatus shown is only illustrative and that the invention can be carried out by other means.

What I claim is:

45 1. A turbine having high and low pressure stages, in combination with rows of wheel-buckets in each of the high-pressure stages for abstracting the energy of the motive fluid by successive fractions, a single row of 50 wheel-buckets in each of the low-pressure stages for abstracting the energy of the fluid in each stage in a single operation, nozzles for expanding and discharging fluid to the high-pressure stages, nozzles or devices for 55 discharging fluid to the low-pressure stages, and partitions which are located between the high-pressure stages only.

2. A turbine having high and low pressure stages, in combination with rows of wheel-buckets in each of the high-pressure stages, for abstracting the energy of the motive fluid by successive fractions, nozzles or devices which extend over a limited arc and 60 discharge motive fluid against a portion 65 only of the buckets in each of the high-pres-

sure stages for abstracting the energy of the fluid in each stage by successive operations, nozzles or devices for the low-pressure stages which surround the wheel-shaft and discharge fluid against all of the wheel-buckets, 70 and partitions which are located between the high-pressure stages only and support the high-pressure nozzles or devices.

3. In a multi-stage turbine, high-pressure stages having annular rows of buckets which 75 are partially supplied with fluid, nozzles or fluid discharging devices for said stages, a plurality of low pressure stages having annular rows of blades which are fully supplied with fluid, nozzles or fluid discharging 80 devices for said stages, and partitions between the high pressure stages only; the fluid in the high pressure stages having greater velocity than in the low-pressure stages. 85

4. A turbine having high and low pressure stages, in combination with rows of wheel buckets in each of the high pressure stages for abstracting the energy of the fluid by successive fractions, nozzles or devices 90 which extend over a limited arc and discharge fluid against a portion only of said buckets in a given unit of time, a single annular row of wheel buckets in each of the low-pressure stages and nozzles or devices 95 for the low-pressure stages which surround the wheel-shaft and discharge fluid against all of the wheel-buckets, and partitions which are located between the high-pressure stages only and support the high-pressure 100 nozzles or devices.

5. In a multi-stage elastic fluid turbine, a plurality of high-pressure stages, each of which includes a complete running wheel equipped with a plurality of rows of buckets for 105 fractionally abstracting fluid energy and nozzles or devices for discharging fluid to the high-pressure stages, a plurality of low-pressure stages, the buckets of which are mounted on one or more drums or wheels, an annular row of nozzles or devices for each 110 low pressure stage for discharging fluid to the entire row of buckets thereof and partitions which are located between the high pressure stages only. 115

6. A turbine having high and low pressure stages, in combination with rows of wheel-buckets in each of the high-pressure stages for abstracting the energy of the motive fluid by successive fractions, nozzles or devices which extend over a limited arc and discharge motive fluid against a portion only of the buckets in each of the high-pressure stages, the nozzles of the high-pressure stages converting a greater percentage of the pressure into velocity than those of the low-pressure stages, nozzles or devices for the low-pressure stages which surround the wheel shaft and discharge fluid against all of the wheel buckets, and 120 125 130

partitions which are located between the high-pressure stages only and support the high-pressure nozzles or devices.

7. In an elastic fluid turbine the combination of a casing having stuffing-boxes in the ends, and a piston-chamber at one end connected with the motive-fluid space at the other end, a rotary shaft passing through said stuffing boxes, high and low pressure members mounted on said shaft within the casing and each provided with vanes arranged in circular series, nozzles arranged to deliver motive fluid simultaneously to a part only of the vanes of the high-pressure member, a chamber arranged to receive the motive fluid from the high pressure member and to deliver it simultaneously to the entire initial series of vanes of the low-pressure member, and a balance piston connected with the rotary part of the turbine and fitted in said piston-chamber, substantially as described.

8. In an elastic fluid turbine the combination of a casing having stuffing-boxes in the ends, an exhaust-chamber in one end and a piston-chamber in the other end connected with said exhaust-chamber, a rotary shaft passing axially through said casing and stuffing-boxes, high and low pressure members mounted on said shaft and each provided with vanes arranged in circular series, nozzles arranged to deliver motive fluid to a part only of the vanes of the high-

pressure member, a chamber within said casing arranged to receive the motive fluid from the high-pressure member and to deliver it simultaneously to all the vanes of the first series of said low-pressure member, and a balance-piston fitted in said piston-chamber and attached to one of said rotary members, substantially as described.

9. In an elastic fluid turbine the combination of coaxial rotary impulse and reaction members each provided with vanes arranged in circular series, a casing inclosing said members and provided with guide-vanes arranged to coöperate with the vanes of the rotary members, means for supplying motive fluid to the vanes of the impulse member, a chamber arranged to receive the motive fluid from the impulse member and deliver it to the vanes of the reaction member, and a balancing piston attached to one end of the rotating part of the turbine and working in a chamber which is connected with the motive-fluid space to which the opposite end of said rotating part is exposed, substantially as described.

In testimony whereof, I have hereunto subscribed my name this 25th day of February, 1907.

FRANCIS HODGKINSON
